FIG.5

FIG. 1 is a perspective view of a watch band showing my new design;

FIG. 2 is a plan view of one end of the watch band illustrated in FIG. 1;

FIG. 3 is an edge view of the end section of the bracelet;

FIG. 4 is a transverse section on lines 4—4 of FIG. 2; and

FIG. 5 is a fragmentary longitudinal section of an enlarged scale at the position indicated by lines 5—5 of FIG. 2.

The dominant features of my design reside in the portions shown in full lines.

I claim:

The ornamental design for a watch band or the like, as shown and described.
